UNITED STATES PATENT OFFICE

FREDERICK F. HEITZIG, OF FIELDON, ILLINOIS

CIRCLE DIVIDER

Application filed June 3, 1929. Serial No. 368,046.

This invention relates to geometrical instruments and has as its primary object the provision of a simple and accurate instrument for use in dividing circles of different diameters into any desired number of equal parts.

Another very important object of this invention is to provide a device of the above set forth character which is very simple in construction, economical and simple to handle with efficiency.

Another very important object of the invention is to provide a device of this character for use in all kinds of shop and drafting work and which will be found to be of great aid in dividing circles into any given number of equal parts.

With the above and numerous other objects in view, the invention consists in the construction and combination of parts of which a preferred embodiment is shown in the drawings, wherein:

Figure 1 is a top plan view of the device constructed in accordance with my invention and showing the same as applied to a disc or circle to be divided.

Figure 2 is an edge elevation thereof.

Figure 3 is a front elevation showing the manner in which the graduated strap is disposed about and affixed in position to the semi-circular frame.

Figure 4 is a section taken substantially on the line 4—4 of Figure 1.

Figure 5 is a perspective view of one of the marker members.

Figure 6 is a vertical transverse section taken through the backing member.

With reference more in detail to the drawings, it will be seen that my improved circle divider comprises a substantially semi-circular frame member designated generally by the reference character 5, said member comprising a substantially flat bar 6, formed of metal or any other suitable material, said bar 6 at its opposite end merging upwardly and having formed integral therewith the adjacent end of the semi-circular backing member 7. The inner longitudinal edge of the bar 6 constitutes a diameter and intermediate its ends the bar 6 is cut away as at 8, so as to

provide the center point 9. The semi-circular backing member 7 is at its ends formed integrally with the ends of the bars 6 and said member 7 may be also formed of metal or material similar to the material from which the bar 6 is made. It is to be noted that the member 7 is in a vertical plane or in a plane at right angles to the bar 6. At its bottom edge, the member 7 is provided with a relatively narrow rim 8 providing a ledge or shoulder extending for the full length of the said member 7. A very thin flexible bar or strap 10, said strap or bar preferably of spring metal is anchored at one end to one extremity of the member 7, as 65 at 11.

On one face thereof, the strap 10 is provided with a suitable graduation 12. The strap 10 is consequently used in the nature of a protractor. A plurality of pointers or markers 13 are adapted for detachable association with the strap or protractor 10, and as shown in Figure 5, each of the markers comprise a shank portion 14 being bevelled at one end as at 15 and the opposite end of the shank 14 merging into a hook 16, for engagement with the upper edge of the strap or protractor 10. At its free end, the strap 10 is provided with a right angularly disposed plate 17, and in this connection it is to be mentioned that the strap 10 is adapted to be disposed about the semi-circular backing member 7 the lower edge of said strap 10 being adapted to rest on the bottom rim 8 as shown to advantage in Figure 3, and said strap is clamped in position about the backing member 7, through the medium of a hook 18, which engages the opposite extremity of the backing member 7, said hook 18 being provided with a shank portion 19, which extends downwardly along the plate 17 for securing the same against the backing member 7 as shown to advantage in Figure 4. It is to be understood, of course, that the lower edge of the strap 10 and right angularly disposed plate 17 is normally spaced from the work, and that the bevelled extremities 15 of the marker 13 extend downwardly beyond the lower edge of the strap 10 to contact with the work. The member 10 being of flexible spring like ma-

terial, it will be seen that when the same is disposed about the backing member 7, the right angularly disposed plate 17 will engage with the end of the member 7, and thus prevent the strap 10 from swinging back out of position upon the said backing member 7. An elongated rigid rod 20 is provided at one end with an eye 20' through which a pin 21 extending from the top edge of the member 7 protrudes for holding said rod in engagement with the member 7.

At its opposite end, the rod 20 is also provided with an eye 20'', to permit the securing of said end to the end of the strap 10 as at 21'. Thus it will be seen that the rod 20 when used in this manner enables one to place and retain the strap or protractor 10 so that it is perpendicular to the diameter of the circle along the inner edge of the bar 6.

20 The protractor strap 10, being of a flexible springy material would, unless clamped, in position about the member 7, naturally stand perpendicular to the work and nearly perpendicular to the diameter. It is also to be noted that the strap 10 is of a width less than the width of the semi-circular backing member 7 as is clearly illustrated in Figure 3. Thus it will be seen that when the strap 10 is clamped about the backing member 7, the lower edge of the strap 10 will rest upon the rim 8 of the member 7, as clearly illustrated.

The manner in which the device is to be used will be best illustrated in the following manner. As an illustration of its use, the following problem is proposed.

Given any arc of a circle, A, D, the circle being designated generally by the reference character P. The circle having its center as at O. It is now required to divide the arc AD into, by way of example, three parts. In dividing the arc AD first draw the radii AO and DO. The instrument is then placed so that the center point 9 of the member 6 of the instrument coincides with the center O of the circle P. The protractor or strap 10 is then placed about the member 7 and clamped in place through the medium of the hook 18 as hereinbefore more fully described. Two of the pointer or markers 13 are then arranged on the member 10, so that they touch the radii as at A-1 and D-1. The arc A-1, D-1 should then be drawn around the edge of the member 7. The protractor 10 is then unclamped and moved out to the position shown in Figure 1, that is to a straight line and at a tangent to the member 7. The rigid member 17 is then utilized to hold the protractor or strap 10 in this position.

60 The position of the two outside pointers or markers 13 is then designated as at A-2 and B-2, thus it will be seen that A-2, B-2 is a straight line equal in length to the arc AD. By geometric construction or rather through

65 the medium of the graduations on the mem-

ber 10, the distance A-2, D-2 is divided into the required number of segments, the inner space pointer or markers 13, being placed on the bar 10 so as to mark this division. The member 10 is then again clamped about the member 7 and the position of the last mentioned or inner pointers or markers 13 is then marked as at B-2 and C-2. The instruments may be now removed and the radii intercepting the arc A-D as to B and C is then drawn. Hence then, A-2, B-1 is equal to B-1 C-1 equals C-1 D-2 equals the arc A-1 B-2 equals arc B-2 C-2 equals arc C-2 D-1. Therefore arc A B equals arc B C equals arc C D. Thus the arc A D has been divided into an equal number of parts which in this case was three equal parts.

From the foregoing then, it will be seen that I have provided a very simple device for dividing a circle, whereby the same may be divided into equal parts accurately and with a minimum expenditure of effort. It is also to be understood that while I have herein shown and described the device as being of semi-circular form, it is to be understood that the same may be of entire circular form if desired.

While I have herein shown and described the preferred embodiment of my invention it is to be understood that the same is susceptible to changes fully comprehended by the spirit of the invention as herein described and the scope of the appended claims.

What is claimed is:

1. In a circle divider, an elongated flat bar, said bar being formed intermediate its ends to provide a center point, and a flexible strap formed of spring material having one end anchored to one end of said bar, and said strap adapted to be disposed in a semi-circular position, means for securing the free end of said strap to the opposite end of said bar, said strap being provided with a graduated scale, and detachable marker members for the strap adapted to be disposed in alignment with the graduations thereon.

2. In a circle divider, a center point formed thereon adapted to coincide with the center of a circle to be divided, an elongated strap formed of flexible spring material anchored to the frame and adapted to be disposed thereabout in a semi-circular position, means for clamping the free end of the strap in set position about the frame, said strap being provided with a graduated scale, and markers having hooked engagement with the strap and adapted for alignment with the graduations on said strap.

3. In a circle divider, a frame of substantially semi-circular contour, the straight edge of the frame having a center point formed thereon adapted to coincide with the circle to be divided, an elongated flexible

- spring like strap anchored to said frame at one end of its straight edge portion, said strap adapted to be disposed about the semi-circular portion of the frame, means for detachably securing the free end of said strap in position about the frame, a rigid member adapted to be detachably secured to the frame and to the free end of said strap for holding said strap at a tangent to the frame, and said strap being provided with a graduated scale formed thereon, and separable markers for the strap and adapted to be disposed thereon in alignment with the graduations.
- 15 4. In a circle divider, a substantially semi-circular frame member, said frame member comprising a straight edge portion, and a semi-circular backing portion having its ends formed integrally with the opposite ends of the straight edge portions, an elongated flexible spring-like strap having graduations formed thereon and having one end thereof anchored to said frame at one end of said straight edge portion, said strap adapted to be disposed about the semi-circular backing portion of the frame, said strap being formed at its free end with means for engaging the frame for holding the strap in said positions, a detachable clamping means for securing said strap in clamped position about the frame, an elongated rigid member adapted to be secured at one end to said frame, the opposite end of said rigid member adapted to engage the free end of said strap for holding said strap at a tangent to said frame, and markers adapted for detachable association with said strap for indicating certain divisional portions of the strap.
- 20 5. A device for dividing a circle comprising a relatively stationary member of elongated configuration formed intermediate its ends to provide a center point and an elongated graduated flexible member adjacent one end thereof fixedly secured to one end of said first mentioned member and normally extending at right angles to said first mentioned member, and markers movable on said flexible member and against which markers the graduations on said flexible member may be read.
- 25 6. In a circle divider, an elongated relatively rigid member formed intermediate its ends to provide a center point, an elongated flexible member at one end thereof secured to one end of said first mentioned member and normally extending at right angles thereto, said flexible member adapted to be bent in the arc of a circle with its free end engaging the free end of said first mentioned member, said flexible member having graduations formed thereon.
- 30 7. In a circle divider, an elongated relatively rigid member formed intermediate its ends to provide a center point, an elongated flexible member at one end thereof secured
- to one end of said first mentioned member and normally extending at right angles thereto, said flexible member adapted to be bent in the arc of a circle with its free end engaging the free end of said first mentioned member, said flexible member having graduations formed thereon.
- 35 8. In a circle divider, a substantially semi-circular frame member, said frame member comprising a straight edge portion, and a semi-circular backing portion having its ends formed integrally with the opposite ends of the straight edge portions, an elongated flexible strap having graduations formed thereon and having one end thereof anchored to said frame at one end of said straight edge portion, said strap adapted to be disposed about the semi-circular backing portion of the frame, said strap being formed at its free end with means for engaging the frame for holding the strap in said positions, a detachable clamping means for securing said strap in clamped position about the frame, an elongated rigid member adapted to be secured at one end to said frame, the opposite end of said rigid member adapted to engage the free end of said strap for holding said strap at a tangent to said frame, and markers adapted for detachable association with said strap for indicating certain divisional portions of the strap.
- 40 9. A device for dividing a circle comprising a relatively stationary member of elongated configuration formed intermediate its ends to provide a center point and an elongated graduated flexible member adjacent one end thereof fixedly secured to one end of said first mentioned member and normally extending at right angles to said first mentioned member, and markers movable on said flexible member and against which markers the graduations on said flexible member may be read.
- 45 10. In a circle divider, an elongated relatively rigid member formed intermediate its ends to provide a center point, an elongated flexible member at one end thereof secured to one end of said first mentioned member and normally extending at right angles thereto, said flexible member adapted to be bent in the arc of a circle with its free end engaging the free end of said first mentioned member, said flexible member having graduations formed thereon.
- 50 11. In a circle divider, a substantially semi-circular frame member, said frame member comprising a straight edge portion, and a semi-circular backing portion having its ends formed integrally with the opposite ends of the straight edge portions, an elongated flexible strap having graduations formed thereon and having one end thereof anchored to said frame at one end of said straight edge portion, said strap adapted to be disposed about the semi-circular backing portion of the frame, said strap being formed at its free end with means for engaging the frame for holding the strap in said positions, a detachable clamping means for securing said strap in clamped position about the frame, an elongated rigid member adapted to be secured at one end to said frame, the opposite end of said rigid member adapted to engage the free end of said strap for holding said strap at a tangent to said frame, and markers adapted for detachable association with said strap for indicating certain divisional portions of the strap.
- 55 12. In a circle divider, a substantially semi-circular frame member, said frame member comprising a straight edge portion, and a semi-circular backing portion having its ends formed integrally with the opposite ends of the straight edge portions, an elongated flexible strap having graduations formed thereon and having one end thereof anchored to said frame at one end of said straight edge portion, said strap adapted to be disposed about the semi-circular backing portion of the frame, said strap being formed at its free end with means for engaging the frame for holding the strap in said positions, a detachable clamping means for securing said strap in clamped position about the frame, an elongated rigid member adapted to be secured at one end to said frame, the opposite end of said rigid member adapted to engage the free end of said strap for holding said strap at a tangent to said frame, and markers adapted for detachable association with said strap for indicating certain divisional portions of the strap.
- 60 13. In a circle divider, an elongated relatively rigid member formed intermediate its ends to provide a center point, an elongated flexible member at one end thereof secured to one end of said first mentioned member and normally extending at right angles thereto, said flexible member adapted to be bent in the arc of a circle with its free end engaging the free end of said first mentioned member, said flexible member having graduations formed thereon.
- 65 14. In a circle divider, a substantially semi-circular frame member, said frame member comprising a straight edge portion, and a semi-circular backing portion having its ends formed integrally with the opposite ends of the straight edge portions, an elongated flexible strap having graduations formed thereon and having one end thereof anchored to said frame at one end of said straight edge portion, said strap adapted to be disposed about the semi-circular backing portion of the frame, said strap being formed at its free end with means for engaging the frame for holding the strap in said positions, a detachable clamping means for securing said strap in clamped position about the frame, an elongated rigid member adapted to be secured at one end to said frame, the opposite end of said rigid member adapted to engage the free end of said strap for holding said strap at a tangent to said frame, and markers adapted for detachable association with said strap for indicating certain divisional portions of the strap.
